CIRCUITS-FLAT TYPE SWITCH

John Wicks, Biloxi, Miss., assignor to Automatic Electric Laboratories, Inc., Chicago, Ill., a corporation of Delaware

Application March 9, 1953, Serial No. 341,187

25 Claims. (Cl. 179—18)

This invention relates in general to telephone systems, and more particularly to an automatic system utilizing multi-directional step-by-step switches.

It is an object of this invention to develop new and novel system utilizing a flat type switch capable of moving a plurality of wipers in a selective number of rotary and radial steps.

A feature of this invention is the economy and simplicity achieved in the system described herein, which system utilizes a switch which makes use of only two magnets, one stepping the wipers therein in two directions under the control of the other. The control magnet will release the switch upon its second operation.

Another feature of this invention is the economy achieved by use of a new and novel all-relay control unit, associated with each first selector but preferably mounted separately, which unit will control all selectors and the connector in a switch train set up over the first selector associated therewith.

Another feature is the provision of a new and novel means whereby both local and incoming toll calls will be routed over the same group of connectors and intermediate selectors.

Another feature of this invention is the use of a new and novel connector, wherein one set of wipers extends a call to any predetermined line in either of two groups of lines accessible thereto in response to two digits.

Another feature is the new and novel manner of completing inter-exchange calls over 2-wire trunks without using repeaters.

Further features of this invention will be evident upon a perusal of the following disclosure in which:

Fig. 1 shows a block diagram of a typical substation, customer line, line circuit, finder, and finder-allotter and a schematic diagram of a switch train control unit.

Fig. 2 shows a 100-line first selector switch.

Fig. 3 shows a 100-line intermediate selector switch.

Fig. 4 shows a 100-line connector switch.

Fig. 5 shows the connector bank wiring for an individual line and a P. B. X.

Fig. 6 shows an inter-exchange selector.

Figs. 7 and 7A show the selector bank wiring for inter-exchange calls.

Fig. 8 shows a toll trunk control unit.

Fig. 9 shows a 200-line selector.

Fig. 10 shows a 200-line connector with two sets of wipers.

Fig. 11 shows a 200-line connector with one set of wipers, and

Fig. 12 shows a party-line connector.

These circuits have been developed for use with the flat type switch shown in the co-pending patent application of Hans Sengbusch, Improvements in Flat Type Switches, Serial No. 236,377, filed July 12, 1951, now Patent No. 2,648,408.

The mechanism of the switch is designed so that the stepping magnet will move the wipers in a rotary direc-

2

tion in response to impulses received while the control magnet is energized for a first time; the stepping magnet will move the wipers in a radial direction in response to impulses received while the control magnet is deenergized; and when the control magnet energizes a second time the wipers will be released first in a radial direction, then in the rotary direction. Said Sengbusch switch has a wiper carriage, normally locked against rotation, and a driving segment. When the switch is initially seized in Wicks' system, the control magnet is energized, its operated armature causing the carriage to be unlocked to permit rotational movement and to be locked with the driving segment. A first series of impulses received by the switch operate the driving magnet, which magnet moves the driving segment (and the carriage locked therewith) in a rotary direction. At the end of said series of impulses, the control magnet restores its armature restoring to cause the carriage to be free of the driving segment and to be locked against rotational movement. Gears, mounted on the wiper carriage and cooperating with the wipers and the driving segment, cause the wipers to be moved radially when the driving magnet is again operated to rotate the driving segment. Associated with the driving segment is a detent for preventing restoration 20 of the segment to normal. Associated with the armature of the control magnet is a release pawl which can engage said detent only when the driving segment is off-normal. Therefore, when said control magnet is operated a second time and said driving segment is off-normal, said pawl will engage the detent and remove it from contact with the driving segment; and the carriage, wipers and driving segment will all restore to normal.

The means for energizing the control magnet of a switch for a second time, to control this release, differs in 35 the various switches—i. e. control magnet M290 of the first selector in Fig. 2 is reoperated over release lead 233; M310 of the intermediate selector in Fig. 3, over a circuit including contacts 301 release control relay R300, and M400 of the connector in Fig. 4, over a circuit including contacts 446 of ring cut-off relay R440. This is done in order to avoid the use of a fourth wiper in the selector and connector switches. The first operation of each control magnet is controlled over that conductor in the switch to which the negative side of a subscriber line is extended.

The operation of each stepping magnet is controlled over that conductor in the switch to which the positive side of a subscriber line is extended.

On local calls the ring cut-off relay—i. e. R440 of Fig. 50 4—is operated upon seizure of the switch, restored upon operation of the switching relay—i. e. R420 of Fig. 4—and then reoperated when the call is answered at the called substation. However, on toll calls, the ring cut-off relay is held operated over the extra control conductor—i. e. 55 453—thereby to permit toll connections, with ringing controlled by the operator, such calls being set up over the same group of selectors and connectors as local connections.

The selector shown in Fig. 9 and the connector shown in Fig. 10 have bank terminals for 200-lines arranged in 20 levels of 10 lines for each level. As one set of wipers moves over one set of contacts, the other set moves over a corresponding set of contacts. In the selector, this results in a more rapid search for an idle trunk. In the connector, the desired trunk is determined by the set of incoming conductors over which a call is received.

The connector shown in Fig. 11 has its bank terminals arranged in 10 levels with 20 lines to a level. This connector depends upon the wipers making from 1 to 10 radial steps to switch through to the first 100 lines and from 11 to 20 radial steps to switch through to the second 100 lines.

Inter-exchange calls may be completed either by the use of the control unit of Fig. 1 or under conditions in which the relays of said unit are completely removed from the control circuit. The former is preferable under normal conditions as the control relays will take the place of a repeater on an inter-exchange trunk. The latter is required when it is desired to provide a control circuit from the substation clear of talking bridges or condensers—e. g. on ring-back conditions on party lines. The circuits of Fig. 1 are adapted automatically to one or the other of said two conditions by wiring the selector bank contacts on the trunk lines as shown in Fig. 7 or 7A. Marginal switching relay R120 of Fig. 1 will not operate to clear the control circuit except when connected in series with resistance 700 of Fig. 7A.

Dial tone and busy tone generators are not shown and may be any one of several types well known in the art. It is assumed that one side is grounded so that a path for tone may be completed to a grounded conductor in any one of the control units.

The ringing generator is not shown and may be any one of several types well known in the art.

Local calls

Referring more particularly to Figs. 1, 2, 3 and 4, establishment of a local connection will be described. Assume a four-digit director number system requiring the use of two selectors and a connector as shown in said figures. Conductors 159, 169, 179, 189 and 199 of Fig. 1 will be tied to conductors 231, 232, 233, 234 and 235 of Fig. 2 respectively. Contacts 236, 237, 238 and 239 of Fig. 2 will terminate conductors 343, 344, 345 and 346 of Fig. 3 respectively. Contacts 365, 366, 367 and 368 of Fig. 3 will terminate conductors 451, 452, 453 and 454 of Fig. 4.

Assume a subscriber initiates a call from substation 195 and that the lines 193 and 194 are extended to conductors 117 and 118 in a manner well known in the art. A circuit for operating line relay R100 is completed from ground, through the lower winding of R100, over contacts 109 and 124, conductor 118, extended line 194, substation 195, extended line 193, conductor 117, contacts 121 and 106, through the upper winding of R100 to battery. R100 operates and at contacts 101 completes an obvious circuit for operating hold relay R110. R110 operates and at contacts 111 prepares a circuit for changeover relay R140 and for stepping magnet M210 of the selector; at contacts 112 marks the control unit-selector link busy over private conductor 119 and partially prepares a circuit for switching relay R130; at contacts 113 completes a circuit for operating series relay R145 and control magnet M200 from ground over contacts 113, the lower winding of R145, contacts 163, 175, 132 and 125, conductors 169 and 232, contacts 223 and 216, through the winding of M200 to battery; at contacts 114 again opens the already open release circuit for the selector of Fig. 2. R145 operates, at contacts 147 prepares a circuit for relay R150 and at contacts 149 partially prepares a circuit for changeover relay R160. M200 operates to prepare the switch for rotary stepping and at contacts 202 prepares a holding circuit for itself.

When the operation of R110 closed contacts 115, an alternating current was imposed upon R145 by dial tone equipment (not shown) over contacts 246 and the previously described circuit through relay 245 and control magnet M200. Transformer action in R145 results in the upper winding of R145 picking up the dial tone current fluctuations, and transmitting them to substation 195 over a circuit extending from line 194, conductor 118, contacts 124 and 109, capacitor 103, the upper winding of R145, capacitors 104 and 116, contacts 106 and 121, conductor 117, and line 193 to substation 195.

Assume that the subscriber now dials the number of a substation on another line and thereby transmits impulses over his line to relay R100. When the first digit is dialled,

line relay R100 will restore and reoperate in response to each impulse received. In response to the first impulse, R100 restoring and closing contacts 102, completes an obvious circuit for operating R140 and a circuit for energizing stepping magnet M210, the latter circuit extending from ground, over contacts 127, 102, 111, 134, 122 and 186, conductors 159 and 231, contacts 221, through the winding of M210 to battery. R140 operates and at contacts 141 completes an obvious circuit for operating R150. R150 operating prepares at contacts 154 a circuit for later operating relay R160 in series with R150. M210 energizes to drive the wipers one rotary step. Off-normal contacts 247 are closed to prepare a second operating circuit for M200, off-normal contacts 246 open to remove dial tone from the line, off-normal contacts 217 close to prepare an operating circuit for interrupter relay R185 and to provide an alternate holding circuit for M200, and off-normal contacts 248 close to complete a circuit for operating relay R160 in series with operated relay R150. However R160 does not operate at this time since it is short-circuited by ground at contacts 141. At the end of the first pulse, R100 reoperates and M210 restores. In response to each additional impulse, the wipers will be moved one rotary step. At the end of the first digit, R140 restores, and at contacts 141 removes the ground which was short-circuiting R160. R160 now operates in series with R150 over a circuit extending from ground, over contacts 249, 248 and 225, conductors 234 and 189, contacts 154, the winding of R160, contacts 149 and the winding of R150 to battery. At contacts 161, R160 locks itself independent of springs 149; at contacts 162, further prepares a circuit for operating R185; and at contacts 163, opens the operating circuit of R145 and M200, both of which restore to normal. M200 restores to complete at contacts 201 a circuit for operating R185, said circuit extending from ground, over contacts 229, 211, 201, 217 and 223, conductors 233 and 169, contacts 125, 132, 175 and 162, through the winding of R185 to battery. Restoration of M200 also changes the switch mechanism so that the wipers will thereafter be stepped in a radial direction. R185 operates and at contacts 187 completes a circuit for operating M210, said circuit extending from ground, over contacts 187, conductors 159 and 231, contacts 221, through the winding of M210 to battery. M210 operates, moves the wipers one step radially, and at contacts 211 opens the operating circuit of R185. R185 restores and at contacts 187 opens the operating circuit to M210. M210 restores. If the contacts, upon which wipers 241, 242, 243, and 244 are standing after this first step, terminate in an idle intermediate selector—i. e. the selector shown in Fig. 3, a circuit for operating switching relay R220 will be completed from battery, over resistor 348, contacts 337, conductor 346, contact 239, wiper 244, the upper winding of R220, conductors 235 and 199, the lower winding of R120, and contacts 115 to ground. It will be noted that R120 does not operate in this circuit and will operate only on inter-exchange calls requiring use of repeaters, as will be explained later. R220 operates; at contacts 223, which operate rapidly, opens the operating circuit of R185 to prevent a reoperation thereof when M210 restores; at contacts 221, opens the circuit to M210; at contacts 225, opens the operating circuit of R160 and R150; at contacts 227 and 228 (contact 228 closing first to insure locking of R220), completes a locking circuit for R220 and places ground through R120 on wiper 244; and at contacts 222, 224, 226, and 227 extends the control circuits to contacts 236, 237, 238 and 239 by way of wipers 241, 242, 243 and 244. R150 and R160 of Fig. 1 restore, R160 at contacts 163 completing a circuit for operating R145 and control magnet M310, said circuit extending from ground, over contacts 113, the lower winding of R145, contacts 163, 175, 132 and 125, conductors 169 and 233, contacts 224, wiper 242, contact 237, conductor 344, contacts 333 and 355, through the winding of M310 to

battery. R145 and M310 operate; release control relay R300 operates over a circuit extending from grounded contact 239 (previously described) over conductor 346, contacts 341, through the winding of R300 to battery. R300 will remain energized until ground is removed at contacts 115 by the hold relay R110.

If the intermediate selector of Fig. 3, had been busy, ground would have been placed on its private contact 239 over a circuit similar to that extending from ground over contacts 115, the lower winding of relay R120, conductors 199 and 235, contacts 227, and wiper 244 to contact 239. R220 could not operate to open the circuit for operating R185; R185 would reoperate when M210 restored; M210 would reoperate when R185 reoperated thereby to step the wipers 241, 242, 243, and 244 to the contacts terminating in the next accessible intermediate selector. If the latter selector were busy, the wipers would be stepped to the next contacts in a similar manner and so on until an idle trunk was found or all trunks were found busy. If all trunks were busy, the wipers would be stepped to the eleventh position, whereupon eleventh off-normal contacts 229 would open to prevent another operation of R185, contacts 249 would open to release R160 and R150. When R160 restores, it completes at contacts 163 a circuit, whereby busy tone from the busy tone generator (not shown) may be sent to the calling substation, said circuit extending from ground over contacts 113, the lower winding of R145, contacts 163, 175, 132 and 125, conductors 169 and 232, contacts 223, 217, 201, 211 and 219, and conductor 218 to the busy tone equipment. Transformer action in R145 again results in the signal being induced into the upper winding of R145 and being transmitted to the calling substation in a manner previously described.

Assuming the intermediate selector of Fig. 3 was seized by the first selector as previously described and was found idle, the second digit will now be received over extended lines 194 and 195. It will be noted that, at this time, the only relays in an operated position are the line relay R100, the hold relay R110 and series relay R145 in the control unit, the switching relay R220 in the first selector, and release relay R300 and control magnet M310 in the intermediate selector. The wipers 361, 362, 363 and 364 will be stepped to a predetermined group of lines in response to the second digit, and will hunt for and seize an idle connector (which we will assume is the connector shown in Fig. 4) all in a manner similar to that in which the first selector seized the intermediate selector. It will be noted that, when switching relay R330 operates, it removes the battery at contacts 337 from conductor 346; at contacts 338, extends ground to contact 368 by way of wiper 364; and, at contacts 335, opens the circuit of R150 and R160. Relay R160 restores to close contacts 163, R145 and control magnet M400 operate in series over a circuit extending from ground, over contacts 113, the lower winding of R145, contacts 163, 175, 132 and 125, conductor 169 and 233, contacts 224, wiper 242, contact 237, conductor 344, contacts 334, wiper 362, contact 366, conductor 452, contacts 425 and 457, through the winding of M400 to battery. R145 operates to prepare circuits for operating R150 and R160 as previously described; M400 operating completes at contacts 401 an obvious circuit for operating ring cut-off relay R440; at contacts 402, completes a locking circuit for itself, bypassing off-normal contacts 457, thereby to hold itself operated during the entire third digit; and at contacts 404 prepares a circuit for operating R160 in series with R150. R440 operates; at contacts 445 locks itself operated over a circuit extending from battery, through the upper winding of R440, contacts 445 and 431, conductor 454, to grounded contact 368 (previously described); and at contacts 446 again opens the already open switch release circuit to control magnet M400. Relay R160 restores. It will be noted that line and hold relays R100 and R110,

series relay R145, switching relays R220 and R330, release control relay R300, control magnet M400, and ring cut-off relay R440 are now the only relays in an operated position.

The connector of Fig. 4 is now ready for the third digit. In response to the first impulse of the third digit, R140 and R150 will operate as previously described. In response to the third digit, stepping magnet M410 will be operated over a circuit extending from ground over contacts 127, 134 and 122, conductors 159 and 231, contacts 222, wiper 241, contact 236, conductor 343, contacts 332, wiper 361, contact 365, conductor 451, and contacts 421 to M410, thereby to move the connector wipers 461, 462, 463, and 464 in a rotary direction to a position before a predetermined group of contacts. When the connector wipers take the first step, off-normal contacts 469 will close to complete the prepared circuit for operating R150 in series with R160, but R160 will not operate at this time since its winding is short-circuited by ground at contacts 141; first off-normal contacts 457 will open the operating circuit of M400, but M400 will remain operated over the locking circuit previously described; and off-normal contacts 458 will close to prepare the switch release circuit to M400. At the end of the third digit, changeover relay R140 will release and at contacts 141, remove the short-circuit from the winding of R160. R160 will operate in series with R150 over a circuit extending from ground at contacts 409 and 404, conductor 453, contact 367, wiper 363, contacts 336, conductor 345, contact 238, wiper 243, contacts 226, conductors 234 and 189, contacts 154, the winding of R160, contacts 149 and the winding of R150 to battery. At contacts 163, R160 opens the circuit of R145 and M400 and both restore. R145 restores to prepare at contacts 146 a circuit for operating relay R170. M400 restores to open at contacts 404 the operating circuit of R150 and R160 (both relays restoring) and to open at contacts 401 the original operating circuit to R440; R160 restores to prepare at contacts 164 an operating circuit to the high resistance relay R190; R150 restores to further prepare at contacts 151 the circuit for operating R170; but R440 is held operated over the previously described locking circuit.

The connector is now in a position to receive the fourth digit. It will be noted that, at this time, line and hold relays R100 and R110, switching relays R220 and R330, release control relay R300, and ring cut-off relay R440 are the only relays in the operated position. In response to the first impulse of the fourth digit, R100 releases and R140 operates as previously described. But R140 operating now completes at contacts 141 an obvious circuit for operating relay R170. R170 operates; at contacts 171, opens the already open busy tone circuit; at contacts 172, prepares a locking circuit for itself; at contacts 173, prepares an operating circuit for line busy relay R180; and at contacts 176, prepares a circuit for operating interrupter relay R185.

It will be noted that control magnet M400, when it released, prepared the switch for radial movement of the wipers. In response to the fourth digit, the connector wipers are stepped by magnet M140 to the contacts terminating a predetermined line in that group of lines predetermined by the third digit. Assume the last-named contacts to be 465, 466, 467 and 468. At the end of the fourth digit R100 will reoperate and R140 will restore.

If the predetermined line is idle, R170 will release in response to the restoration of R140; at contacts 177, R170 will prepare a circuit for operating relay R190; and at contacts 175, completes a circuit for operating switching relay R420, said circuit extending from ground, over contacts 113, the lower winding of R145, contacts 163, 175, 132 and 125, conductors 169 and 232, contact 224, wiper 242, contacts 237, conductor 344, contacts 334, wiper 362, contact 366, conductor 452, con-

acts 425 and 403, the lower winding of R420 and wiper 464 to battery (not shown) on contact 468 of the private conductor associated with the predetermined line. R420 will operate but R145 will not operate in series with R420. At contacts 422 and 426, R420 extends the subscriber line circuit; at contacts 424, places ground on one side of the predetermined line (R440 releases to close contacts 443); at contacts 425, opens its own operating circuit but contacts 432 close before contacts 425, and R420 is held operated over a locking circuit extending from grounded contact 368, conductor 454, contacts 432, through the upper winding of R420 to battery; at contacts 427, opens the already open switch release circuit to M400; at contacts 431, opens the locking circuit of R440 and transfers said locking circuit to conductor 453 by means of contacts 429; at contacts 433, puts ground on contact 468 by way of wiper 464, thereby to busy mark the predetermined line; and at contacts 423 completes a ringing circuit to the substation on the predetermined line, said circuit extending from the ringing generator (not shown), over conductor 459, through the lower winding of R440, over contacts 423 and 441, wiper 461, contact 465, over that side of the line terminating in contact 461, through the ringing circuit of the substation associated with said predetermined line, over that side of the line terminating in contact 466, over wiper 462, contacts 443 and 424 to ground, thereby to ring said substation. When the holding circuit of R440 was transferred, relay R190 was operated in series with R440 over a circuit extending from battery, through the upper winding of R440, contacts 445 and 429, conductor 453, contact 367, wiper 363, contacts 336, conductor 345, contact 238, wiper 243, contacts 226, conductors 234 and 189, contacts 164 and 177, through the winding of R190 to ground. R190 operates, but its resistance is high and R440 restores. R440 restoring opens the circuit for operating R190 at contacts 445 and R190 will restore. When R190 operated, it completed at contacts 191 an obvious circuit for operating relay R155 from ground at contacts 139. R155 operates to complete a circuit for operating switching relay R130 in series with itself, however ground over contacts 139 and 191 short-circuits R130. When R190 operates it also completes at contacts 192, a circuit for operating R150, said circuit extending from ground, over contacts 192 and 148, through the winding of R150 to battery. R150 operates and at contacts 139 removes ground from the operating circuit of R155, thereby removing the short-circuit from R130. R130 operating over a circuit extending from ground, over contacts 112, the winding of R130, contacts 157, through the winding of R155 to battery. R150 restores in response to the restoration of R190. R130 operating, extends at contacts 131 and 133 a talking circuit from the calling substation to contacts 442 and 444 of the connector; at contacts 132 and 134, removes the control circuits from both sides of the line; and at contacts 135, prepares a holding circuit for ring cut-off relay R440, as well as short-circuiting R190 to prevent its reoperation. It will be noted that R440 completely restores before R130 operates. When the called subscriber lifts his receiver, the ringing circuit of his substation will be short-circuited in a manner well known in the art; the flow of direct current in the ringing circuit will operate R440. R440 will lock itself operated over a circuit extending from battery, over the upper winding of R440, contacts 445 and 429, conductor 453, contact 367, wiper 363, contacts 336, conductor 345, contact 238, wiper 243, contacts 226, conductors 234 and 189, to ground at contacts 135; at contacts 442 and 444, completes the talking circuit from the calling substation to the called substation and also completes a circuit for operating back-bridge relay R105 which will supply battery for the called line and reverse the connections of relay R100 to the calling line, the former circuit extending from the

calling substation 195, over line 193 extended to conductor 117, contacts 121 and 108, capacitor 103, contacts 133 and 125, conductors 169 and 232, contacts 224, wiper 242, contact 237, conductor 344, contacts 334, wiper 362, contact 366, conductor 452, contacts 426 and 444, wiper 462, contact 466, the line terminating in contact 466, the called substation, the line terminating in contact 465, contact 465, wiper 461, contacts 442 and 422, conductor 451, contact 365, wiper 361, contacts 332, conductor 343, contact 236, wiper 241, contacts 222, conductors 231 and 159, contacts 186, 122 and 131, capacitor 116, contacts 107 and 124, conductor 118 and extended line 194 to substation 195, the latter circuit extending from the grounded lower winding of R105, to contacts 133, over the previously described circuit from contacts 133 to the called substation and back to contacts 131, thence through the upper winding of R105 to battery; relay R440, at contacts 441 and 443, also opens the ringing circuit; and at contacts 446, again opens the already open switch release circuit to magnet M400. It will be noted that at contacts 107 and 108, R105 reverses the battery connections to the calling line, such reversal being utilized in cases where metering is desired as is well known in the art.

If the called line—terminating in contacts 465 and 466—had been busy when seized by the connector of Fig. 4, ground rather than battery would have been connected to private contact 468 associated with the called line. As a result thereof, busy relay R180 would operate before R170 released over a circuit extending from battery, through the winding of R180, over contacts 173, 132 and 125, conductors 169 and 232, contacts 224, wiper 242, contact 237, conductor 344, contacts 334, wiper 362, contact 366, conductor 452, contacts 425 and 403, the lower winding of switching relay R420, wiper 464, to grounded contact 468. R420 will not operate in series with the high resistance winding of R180. R180 puts busy tone from the grounded busy tone equipment (not shown) over conductor 139, contacts 181 and 171, capacitors 104 and 116, contacts 106 and 121, conductor 117, extended line 193, over the called substation 195, extended line 194, conductor 118, contacts 124 and 109, through the lower winding of R100 to ground. At contacts 182, R180 prepares a locking circuit for itself, said circuit being completed at contacts 174 when R170 releases after a short time delay, said circuit extending from the grounded conductor 199 (previously described), over contacts 182 and 174, through the winding of R180 to battery.

With respect to release of the switch train after completion of a call, it will be noted that, when the called party hangs up, the only effect is to restore back-bridge relay R105. When the calling party hangs up, the line circuit 196 and finder 197 will be restored in a manner well known in the art. Also the circuit to line relay R100 is opened and R100 restores. R100 restoring, energizes R140 and opens the circuit to R110. R140 operates; at contacts 141, completes a previously described circuit for operating R170; and at contacts 143, again opens the already open release circuit to M200. After the operation of R140, hold relay R110 releases, at contacts 111, it opens the operating circuit of R140; at contacts 112, opens the operating circuit of R130 and R155 both relays restoring; at contacts 114, prepares a release circuit for M200; and at contacts 115, removes ground from conductor 199 restoring switching relays R220, R330 and R420, and restoring release relay R300.

R300 restoring completes at contacts 301 an obvious circuit for operating M310 a second time, thereby to cause M310 to release the switch of Fig. 3. At release off-normal contacts 342, which are closed from the moment M310 operates a second time until the wipers return to normal, ground is placed upon conductor 346

to prevent seizure of said switch until it has returned to normal. When the wipers return to normal, off-normal contacts 347 open the operating circuit of M310 and the magnet restores. It will be noted that the restoration of R130 will open the operating circuit of back-bridge relay R105 if the called subscriber did not hang up. The intermediate selector is now restored to normal.

R420 restoring, transfers at contacts 429 the holding circuit of R440 back to the private conductor 454 and R440 will restore. R440 restores and at contacts 446 completes an obvious circuit for operating M400 for a second time, thereby to cause M400 to release the switch of Fig. 4. Ground over contacts 401 and 455 to conductor 454 will prevent seizure of the switch until the wipers are restored to normal at which time release off-normal contacts 455 open. The operating circuit of M400 is opened at off-normal contacts 458 when the wipers are restored to normal. R440 may energize upon restoration of release off-normal contacts when the wipers return to normal before M400 releases, but this will be of no consequence and R440 will restore upon restoration of M400. It will be noted that the intermediate selector restored to normal prior to the restoration of the connector and therefore is now restored to normal.

When slow-release relay R140 restores after the release of both the intermediate selector and the connector, it completes a circuit for operating M200 for a second time said circuit extending from ground over contacts 114, 128 and 143, conductors 179 and 233, contacts 247, through the winding of M200 to battery. Operation of M200 causes release of the first selector. M200 restores when off-normal contacts 247 open upon return of the wipers to normal. R180 may operate upon restoration of R130; and R185, upon the restoration of R140; but this will be of no consequence at this time and both relays will release upon restoration of wipers 241, 242, 243 and 244 to normal; R170 will restore the control unit and the first selector will be restored to normal.

Fig. 5 shows typical connector bank contact connections for individual lines and P. B. X trunks. For an individual line, the bank contact 501 connected to the extra control conductor, and contact 505 connected to the private conductor are not connected to each other. The extra-control and private terminals of P. B. X groups are strapped as indicated in Fig. 5—e. g. 502 to 506—except for the last line—i. e. 504 is not strapped to 508. When the connector switch wipers seize the first accessible line of a P. B. X group and said line is busy, ground on the private conductor associated with said line will be placed on the extra-control contact over the strapped connection. Assume contact 467 is the extra-control contact and contact 468 the private contact of said first line. As described with respect to busy lines, ground at contact 468 will operate busy relay R180. R180 operates; and, at contacts 183, prepares a circuit for operating interrupter relay R185; R140 releasing shortly after said seizure completes at contact 142 said circuit for operating R185, the circuit extending from ground at contact 467, over wiper 463, contacts 411 and 428, conductor 453, contact 367, wiper 363, contacts 336, conductor 345, contact 238, wiper 243, contacts 226, conductors 234 and 189, contacts 164, 176, 142 and 183, through the winding of R185 to ground. R185 operates; closes contacts 187 to energize stepping magnet M410 over a circuit extending from ground, over contacts 187, conductors 159 and 231, contacts 222, wiper 241, contact 236, conductor 343, contacts 332, wiper 361, contact 365, conductor 451, contacts 421, through the winding of M410 to battery. M410 energizes, steps the connector wipers to the next set of contacts accessible thereto; and at contacts 411, opens the circuit to R185. R185 restores and M410 restores. If other lines are busy, the same sequence of operations are repeated. If the last line is busy, the extra-control contact will not be grounded, and as with the in-

dividual busy line, R170 restores and puts the busy signal on the calling line. It will be noted that R185 completes at contacts 183 an obvious circuit for holding slow-release relay R170 operated during the hunting operation. If the first accessible P. B. X line is idle, battery will be placed on the private bank contact associated therewith, the switching relay R420 will operate; and the call will be routed in the manner previously described.

Inter-exchange calls

Inter-exchange connections may be set up under the control of the relays in the control unit of Fig. 1, or under conditions in which said relays are completely removed from the circuit. The former condition is preferable since said relays will replace a repeater. The latter condition is required however when it is desired to clear the line of talking bridges or capacitors.

For use under conditions wherein said control unit circuits will replace a repeater, applicant has devised an inter-exchange control unit, shown in Fig. 6, with a pulsing relay R600. Assume a call is initiated at substation 195, and is routed to the local control unit in Fig. 1; assume said local control unit is connected to a first selector similar to that of Fig. 2 as in the local call; assume that the bank contacts of said selector corresponding to contacts 236 and 237 terminate in trunk lines 691 and 692 respectively, which lines are connected to the inter-exchange control unit; that the bank contacts corresponding to contacts 238 and 239 are connected to battery through resistors 710 and 711 respectively of Fig. 7; assume further that the selector of Fig. 2 is connected to the inter-exchange control unit of Fig. 6, therefore connecting conductor 694 to 231, 695 to 232, 696 to 233, 697 to 234 and 698 to 235; and, as in the local call, that bank contacts 236, 237, 238 and 239 terminate in the selector of Fig. 3; and that the bank contacts 365, 366, 367 and 368 terminate in the connector of Fig. 4.

In response to the first digit, assume that the wipers of the selector connected to the local control unit will be stepped in a rotary direction to a position before a group of bank contacts including those contacts terminating trunk lines 691 and 692, and then radially to said last-mentioned contacts, which trunk lines we shall assume are idle, all in a manner similar to that described with respect to local calls. The switching relay of said last-mentioned selector will operate upon said seizure over a circuit similar to one previously described and including battery through resistor 711. As in the local call, relay R160 will restore; but now relay R190 will operate over a circuit extending from battery, over resistor 710, a contact, a wiper and a conductor corresponding to 238, 243, and 234 respectively, conductor 189, contacts 164 and 177, through the winding of R190 to ground. R190 operates; at contacts 192, completes an obvious circuit for holding R150 operated; and, at contacts 191, prepares a circuit for operating relay R155. Upon restoration of R160, R140 and line relay R600 will operate in series over a circuit extending from ground, over contacts 113, the lower winding of R145, contacts 163, 175, 132 and 125, conductor 169, a conductor, contacts, wiper and contact corresponding to 233, 224, 242 and 237 respectively, trunk 692, the winding of R600, contacts 627, trunk 691, a contact, wiper, contacts and conductor corresponding to 236, 241, 222 and 231 respectively, conductor 159, contacts 186, 122 and 134, through the winding of R140 to battery. R145 does not operate in series with R600 and R140 due to its low resistance.

R140 operates and at contacts 141 completes a circuit for operating R155, said circuit extending from ground, over contacts 141, 146, 152 and 191, through the winding of R155 to battery. The winding of switching relay R130 is short-circuited by said ground on contacts 141 to prevent its operation at this time. R600 operates and at contacts 601 completes an obvious circuit for operating hold relay R615. R615 operates; at contacts 616, pre-

paces a pulsing circuit; at contacts 617, prepares a circuit for operating switching relay R625; at contacts 618 completes a circuit, similar to one previously described, for operating series relay R640 and control magnet M200 of its selector in series. A call may be completed to a subscriber line, accessible to the connector of Fig. 4—e. g. the line terminating in contacts 465 and 466, in a manner similar to that previously described for local calls, except that the inter-exchange control unit pulsing circuit is controlled by line relay R600, which relay is in turn controlled by line relay R100 as follows: when R100 deenergizes in response to each impulse, it short-circuits the winding of R600 by closing contacts 102 to apply ground to both sides of R600 and extends the ground from contacts 127 to the winding of R140. As a result, R600 will deenergize and at contacts 602 complete a pulsing circuit similar to that described with respect to local calls to operate the selector and connector to seize a called line. When R100 reenergizes at the end of each impulse, the short-circuit will be removed from R600 so that it will reenergize.

When a connection to an idle line is completed and switching relay R625 is operated in a manner similar to the operation of switching relay R130 as described with respect to local calls, R625 will, at contacts 627, open the series circuit of R600 and R140; and, at contacts 628, place R605 in series with R140. R600 restores, and R605 operates, but R140 will restore when placed in series with the high resistance winding of R605. R140 restores, to remove, at contacts 141, ground from the operating circuit of R155, and R130 will operate in series with R155 over the circuit previously described to prepare the talking circuit and the circuit for operating back-bridge relay R105 as previously described, and also to short-circuit, at contacts 135, the winding of R190 to restore the latter. R150 restores in response to the restoration of R190. The call will then be completed in a manner similar to that in which the local call was completed.

Release of the switch train at the end of a call is similar to that described for the local switch train.

If an inter-exchange call is to be made over a trunk requiring a repeater—e. g. when a connection to another type of system is to be established or when the completion of a reverting call requires the utilization of a reverting call switch in another exchange, it is necessary to remove the relays of the local control unit from the line. This is accomplished by wiring the selector bank contacts associated with the trunk line, over which said connections are to be made, as shown in Fig. 7A, wherein resistance 700 is of low resistance so that switching relay R120 will operate in series with said resistance. In a manner similar to that in which local connections were set up, connections may be completed to an idle trunk, the contacts of which are wired as shown in Fig. 7A. Assuming that the selector of Fig. 2 was used to make such connections, the switching relay R220 will operate and lock itself in a manner previously described. R120 will operate in series with resistance 700 over a circuit extending from ground, over contacts 115, the lower winding of R120, conductor 199, conductor 235, contacts 227, wiper 244, the wiper contact connected to resistance 700, and resistance 700 to battery. At contacts 129, R120 completes a locking circuit for itself; at contacts 123 and 126, extends the calling line to relay R720, free of all control relays in the control unit of Fig. 1; and at contacts 128 opens the circuit for reoperating M200. R720 energizes over the calling loop and, at contacts 721, completes an obvious circuit for energizing relay R730. R730 operates to remove, at contacts 731, battery from the private conductor 199 and to place ground thereon thereby to busy mark the trunk. When R120 operates, it also opens the operating circuit of line relay R100 at contacts 121 and 124 and extends ground over contacts 127b to conductor 119 to busy mark the control unit. R100 releases. R140 and R170 operate but this is of no conse-

quence since they will restore after R110 restores in response to the restoration of R100. The call may now be routed to the distant exchange in a manner well known in the art.

Incoming toll calls

Incoming toll calls will be routed by a telephone operator over a toll board trunk selector such as that shown in Fig. 8. Provision is made for preventing the automatic restoration of the ring cut-off relay when a connector extends toll connections to an idle called line so that ringing of said called line can be controlled by the operator. Toll connections are set up over the same group of intermediate selectors and connectors used for completing local connections, the necessity of separate toll train switches for operator-controlled ringing being eliminated. The control circuits of Fig. 8 are otherwise similar to those of Fig. 1.

Assume that a toll call is routed by an operator to the toll board control unit of Fig. 8. Assume that said unit is connected to the selector of Fig. 2, the conductor 859 being connected to conductor 231, 869 to 232, 879 to 235, 889 to 233, and 899 to 234; that the selector of Fig. 3 is accessible to the selector of Fig. 2 and contacts 236, 237, 238 and 239 terminate in the selector of Fig. 3; and that the connector of Fig. 4 terminates in contacts 365, 366, 367 and 368. In response to impulses received by pulsing relay R800 over conductor 829, a toll connection will be set up over the first and the intermediate selectors under the control of the toll board control unit in a manner similar to that in which the local connections are set up, as previously described. Also the operation of the control unit and the connector in response to a third digit dialled by the operator will be similar to that described with respect to local calls. Therefore, at the end of the third digit, relays R800, R810, R830, R835, M400 and R840 will be operated; the connector wipers will be standing before the bank contacts of a group of lines associated therewith—which contacts we will assume include contacts 365, 366, 367 and 368; relay R830 will restore; relay R850 will operate in series with relay R840; R850, operating, opens the operating circuit of series relay R835 and control magnet M400, both restoring; M400, restoring, opens the operating circuit of R840 and R850, both relays restoring; and the ring cut-off relay is held operated over a locking circuit, all in a manner similar to that described with respect to the establishment of a local connection.

Now, when a fourth digit is dialled by the operator, relay R830 is again operated in response to the restoration of line relay R800, and, at contacts 831, completes an obvious circuit for operating relay R860. In response to the fourth digit, the connector wipers are stepped by M410 to the contacts terminating the called line—e. g. contacts 465, 466, 467 and 468. If the called line is busy, a busy signal will be put upon coil 898 by an operation of busy relay R870 and a restoration of relays R830 and R860, in a manner similar to that described for local calls. The busy signal is induced into coil 897 and sent to the operator over conductor 809. If the line is idle, the switching relay R420 will be operated over a circuit similar to one, previously described, in response to the restoration of R860. As previously described, R420 will transfer the holding circuit of ring cut-off relay R440 to the extra control conductor 453 and relay R890 will operate in series with R440. However, when R890 operates, it completes, at contacts 891, an obvious circuit for operating switching relay R820. R820 operating before R440 releases, completes, at contacts 826, a circuit for holding R440 operated and for short-circuiting the winding of R890, said circuit extending from ground, over contacts 826 and 806, conductors 899 and 234, contacts 226, wiper 243, contact 238, conductor 345, contacts 336, wiper 363, contact 367, conductor 453, contacts 429 and 445, through the winding of R440 to battery; and, at contacts 825, completes an obvious locking circuit from ground at contacts

812. R890 restores, R820 prepares the talking circuit at contacts 821 and 823; and R440, remaining operated, keeps the ringing current off of the called line. When the operator desires the called line to be rung, she will cause relay R805 to be energized in a manner well known in the art; and, at contacts 886, the last mentioned holding circuit for R440 will be opened; R890 will again operate in series with R440; R440 will restore when in series with the high resistance winding of R890; and at contacts 445 the operating circuit of R890 will be opened, the latter restoring; when R440 restores, ringing current will be extended to the called line as previously described. When the called party answers, back-ridge relay R815 and ring cut-off relay R440 will operate, the latter completing the talking circuit from the called substation to conductors 809 and 819. The toll connections will then be completed by the operator in a manner well known in the art.

200-line selector

Referring more particularly to Fig. 9, it will be noted that both sets of wipers hunt simultaneously for an idle trunk, the upper set testing a trunk in one group of trunks as the lower set tests a corresponding trunk in a second group. The selector is wired as an intermediate selector similar to that of Fig. 3 as shown by the use of a release initiating relay R910 and battery over resistor 967; but obviously can be wired as a first selector.

When said selector is seized by a previous switch after the initiation of a call, the control magnet M900 will operate in series with the series relay—e. g. R145 of the local control unit. Except as otherwise noted, operation of this 200-line selector is the same as that of a 100-line selector. With M900 operated, stepping magnet M910 will step both sets of wipers to positions before predetermined groups of contacts in response to a series of impulses. Control magnet M900 will be restored and the selector radial stepping circuit will step both sets of wipers across bank contacts until an idle trunk is seized.

If two trunks, simultaneously seized by the two sets of wipers, are both idle, both switching relays, R930 and R940, will operate simultaneously. However, R930, operating contacts 938 opens the operating circuit of R940 and the latter restores. The call will therefore be extended over the upper set of wipers.

Obviously, if the trunk seized by the upper set of wipers is idle and that seized by the lower set is busy, the call will be extended over the upper set of wipers.

If the trunk seized by the lower set of wipers is idle and the other trunk busy, then only switching relay R940 will operate. At contacts 949, R940 will lock itself operated over the lower winding; and the call will be extended over the lower set of wipers. The resistances of the upper winding of R930 and the lower winding of R940 are such that if, after R940 operates and locks, the trunk, upon which the upper wipers are standing, becomes idle and battery is therefore placed on wiper 972, R930 will not operate over its upper winding. Therefore a connection completed over the lower set of wipers cannot be broken at contacts on R930, once R940 has operated and locked.

200-line connector with two sets of wipers

Referring more particularly to Fig. 10, it will be noted that both sets of wipers simultaneously seize different outlets; that each set has access to 100-lines; and that one control magnet, one stepping magnet, and one ring cut-off relay are used for completing a call to any one of the 200-lines. Also the operation of the 200-line connector is similar to that of the 100-line connector unless otherwise noted, the connection to be made depending upon which of the two sets of incoming conductors is the set over which a call is being routed. Thus, if a call is routed over the upper set of incoming conductors, a connection will be completed to an outlet accessible to the upper set of wipers; and, if routed over the lower set of conductors, a connection will be completed to an outlet

accessible to the lower set of wipers. The selection of the upper or lower set of incoming conductors would obviously be made in the next preceding stage in the switch train in a manner well known in the art.

Assume the connector of Fig. 10 is seized over the upper set of conductors 1081, 1082, 1083 and 1084. The control magnet M1000 will operate together with the series relay of the control unit now controlling said connector. Pulses of the first digit received by stepping magnet M1010 over conductor 1081 and contacts 1042 will cause said magnet to step both sets of wipers to predetermined groups of outlets. Control magnet M1000 de-energizes; and, in response to a second digit received, magnet M1010 will step each set of wipers to a predetermined outlet. But obviously only the upper switching relay will operate if the outlets are idle, since only its incoming conductors are connected to the switch train over which the call is being routed. The call will be completed in a manner similar to that previously described for a 100-line connector.

A call routed over the lower set of incoming conductors will be extended over the lower set of wipers in a similar manner.

200-line connector with one set of wipers

Referring more particularly to Fig. 11, it will be noted that the bank contacts accessible to wipers 1181, 1182, 1183 and 1184 are arranged in 10 rows of 20 lines each; and that a first and second control magnets, M1110 and M1100 respectively, are used.

If the connector is seized over the upper conductors 1161, 1162, 1163 and 1164, the proper connections will be made under the control of M1110 to one of the first 10 lines of one row in a manner similar to that in which the 100-line connector completed the connections.

However, assuming a local call has been extended over the control unit of Fig. 1 and the selectors of Fig. 2 and Fig. 3 in a manner previously described, to the connector of Fig. 11 over the lower set of conductors 1165, 1166, 1167 and 1168, said connector will step its wipers under the control of the first control magnet M1110 to a predetermined row of outlets in response to the first digit received, in a manner similar to that in which the connector of Fig. 4 operates. At the end of said first digit received by the connector, relay R140 will restore in a manner similar to that previously described; but now the second control magnet M1100 operates in series with R160 and R150 over a circuit extending from ground over contacts 1171, the lower winding of M1100, contacts 1113, conductor 1167, contact 367, wiper 363, contacts 336, conductor 345, contact 238, wiper 243, contacts 226, conductors 234 and 189, contacts 154, the winding of R160, contacts 149, through the winding of R150 to battery. R145 and M1110 restore, but M1100 is held operated over an obvious holding circuit including its upper winding and contacts 1105, and R160 and R150 are held operated over a circuit including contacts 1102, and similar to its operating circuit. M1100 operating and M1110 restoring complete at contacts 1104 and 1115 a circuit for operating interrupter relay R185, said circuit extending from ground, over contacts 1104, 1122, 1115 and 1133, conductor 1166, contact 366, wiper 362, contacts 334, conductor 344, contact 237, wiper 242, contacts 224, conductor 232 and 169, contacts 125, 132, 175, and 162, and thence through the winding of R185 to battery. Said circuit will be opened at contacts 1122 when stepping magnet M1120 operates in response to the operation of R185. The wipers of the connector will be self-stepped to the tenth outlet of said predetermined row of outlets at which time the tenth off-normal contacts 1171 will open, relay R160 and R150 will restore, and R185 cannot re-operate since its operating circuit will be open at contacts 162.

In response to a second digit received, the connector wipers will be stepped to a predetermined one of the last

ten outlets of said predetermined line. At the end of the first impulse of said second digit, the eleventh off-normal contacts 1169 will open; M1100 will restore; and, at contacts 1103, the operating circuit of switching relay R1130 will be prepared. Connections will be completed in a manner similar to that previously described with respect to the connector of Fig. 4.

It will be noted that numerous combinations of the various selectors and connectors shown by applicant may be utilized in a switch train depending upon the requirements of the exchange in question. The use of such combinations is well known in the art and, it is felt, need not be discussed here.

The party line connector

Referring more particularly to the party line connector shown in Fig. 12, it will be noted that the circuits differ noticeably from those of the connector shown in Fig. 4. This is due to the provision for selective ringing—5 codes being available for each line as shown. Ringing voltage is supplied over a typical minor switch arrangement in a manner well known in the art. Except as otherwise noted, the operation of the party line connector is the same as that of the connector shown in Fig. 4.

Assume a call is extended by the control unit of Fig. 1 and the selectors of Fig. 2 and Fig. 3 to the connector of Fig. 12. Control magnet M1240 operates in series with relay R145 and, at contacts 1243, completes an obvious circuit for operating relay R1230. R1230 completes, at contacts 1234, an obvious circuit for operating relay R1220; and, at contacts 1233, prepares the circuit for operating stepping magnet M1250. Ring cut-off relay R1280 is operated by ground on private conductor 1214. In response to a digit received, the connector wipers are stepped by M1250 to a predetermined group of outlets. M1240 restores at the end of the first digit received, thereby to prepare the switch for radial movement. At contacts 1243, M1240 opens the operating circuit of R1230; but the latter is held operated over a circuit extending from ground on the private conductor 1214, over radial off-normal contacts 1207, contacts 1237, through the winding of R1230 to battery. In response to a second digit received, the wipers are stepped to a predetermined outlet. Radial off-normal contacts 1207 open the holding circuit of R1230; but M1250, at contacts 1252, keeps R1230 operated until the end of the second digit when R1230 restores.

If the predetermined outlet is busy, ground on its private conductor is extended over wiper 1217, contacts 1236, 1242 and 1265, conductor 1212, and over a previously described circuit to busy relay R180, the latter operating before R1230 restores. Busy signal is then relayed to the calling party in a manner previously described.

If said predetermined outlet were idle, battery is present on its private conductor, and R1230 restoring opens, at contacts 1234, the operating circuit of R1220, the latter being held operated over a circuit extending from the grounded private conductor 1214, over the minor switch off-normal contacts 1202, contacts 1221, through the lower winding of R1220 to battery. At contacts 1232, R1230 prepares the operating circuit of minor switch magnet M1210. In response to a third digit received, a predetermined ringing code—e. g. that associated with conductor 1291—is selected by M1210; at off-normal contacts 1201, a circuit for operating the minor switch release magnet M1200 is prepared; at the end of said third digit, R1220 restores to complete, at contacts 1222, a circuit for operating switching relay R1260, said circuit similar to that for operating switching relay R420 of Fig. 4. Ringing current is supplied to the called line from a ringing generator (not shown), over conductor 1291, contact 1292, wiper 1293, contacts 1294, the multiplied contacts of the minor switch, the lower winding of R1280, contacts 1261 of switching relay R1260,

contacts 1281 of ring cut-off relay R1280, wiper 1215, one side of the called line, the called substation ringing device, the other side of the called line, wiper 1216 and contacts 1283 and 1264 to ground. As with the operation of the connector of Fig. 4, R1280 will operate and lock when the called party answers.

While there has been described what is at present considered to be the preferred embodiment of the invention, it will be understood that various modifications may be made therein, and it is contemplated to cover in the appended claims all such modifications as fall within the true spirit and scope of the invention. Applicant's preferred embodiment shows the selective switches stripped of the control means but it is obvious that each switch could have its own individual control means.

What is claimed is:

1. In a telephone system including an automatic switch having wipers with a normal position and having a single driving means together with a control magnet and an armature-controlled mechanism for causing an operation of said driving means while said magnet is energized to move said wipers in one direction and for causing an operation of said driving means while said magnet is deenergized to move said wipers in another direction, a calling line over which impulses are received, means associated with said line and switch responsive to the initiation of a call over said calling line for energizing said control magnet, means responsive to each impulse in a series of impulses thereafter received over said calling line for operating said driving means, a changeover relay, means responsive to the termination of said series of impulses for operating said relay, means responsive to the operation of said relay for deenergizing said magnet, means for thereafter selectively operating said driving means and for switching through connections to said wipers, means responsive to the termination of said call for energizing said magnet a second time, and an armature-controlled mechanism for restoring said wipers to normal in response to said second energization of said magnet.

2. In an automatic switch having a switching member with a normal position and having a single driving means together with a control magnet with means for causing an operation of said driving means while said magnet is energized to move said member in one direction and for causing an operation of said driving means while said magnet is deenergized to move said member in another direction, incoming conductors over which said switch is seized and over which series of impulses are received, means responsive to the seizure of the switch for energizing said magnet, means responsive to each impulse in a series of impulses thereafter received over said conductors for operating said driving means, a changeover relay, means responsive to the termination of said series of impulses for operating said relay, means responsive to said operation of the relay for deenergizing said magnet, means for thereafter selectively operating said driving means and for switching through connections from said conductors to said member, means responsive to the initiation of the release of the switch for energizing said control magnet a second time, and a mechanism including the armature on said magnet operated and effective in response to said second energization of the magnet for restoring said member to normal.

3. In a telephone system including an automatic switch with wipers having a normal position and including a plurality of lines, together with means for connecting a calling one of said lines to said switch, for sending impulses over said calling line and for thereafter disconnecting said calling line therefrom, said switch comprising a control magnet, means responsive to the connection of said calling line to the switch for energizing said magnet, a single driving means, means responsive to each impulse in a series of impulses received over said calling line for operating said driving means, armature-controlled

means operated and effective in response to the energization of said magnet for causing the operations of said driving means to move said wipers in one direction, an interrupter relay, a changeover relay, means responsive to the termination of said series of impulses for operating said changeover relay, contacts on said changeover relay operated for deenergization of the control magnet and for operating the interrupter relay, means responsive to the operation of said interrupter relay for selectively operating said driving means and for switching through connections from said calling line to said wipers, armature-controlled means operated and effective in response to the deenergization of the magnet for causing said last-mentioned operation of the driving means to move the wipers in another direction, means responsive to the disconnection of the calling line from the switch for energizing said magnet a second time, and an armature-controlled mechanism operated and effective only in response to said second energization of the control magnet for restoring said wipers to normal.

4. In a telephone system including an automatic switch with wipers having a normal position and including a plurality of lines together with means for connecting a calling one of said lines to said switch, for sending impulses over said calling line and for thereafter disconnecting said calling line therefrom, said switch comprising a control magnet, means responsive to the connection of the calling line to the switch for energizing said control magnet, a single driving means, means responsive to each impulse in a series of impulses received over said calling line for operating said driving means, armature-controlled means operated and effective in response to the energization of said magnet for causing said operations of the driving means to move said wipers in one direction, a changeover relay, means responsive to the termination of said series of impulses for operating said relay, contacts on said relay operated to restore said magnet, contacts on said magnet restored to restore said changeover magnet, said second mentioned means operated responsive to each impulse in a second series of impulses received over said calling line for operating said driving means, armature-controlled means operated and effective in response to the deenergization of said magnet for causing said last-mentioned operations of the driving means to move said wipers in another direction, means responsive only to the termination of said second series of impulses for switching through connections from said calling line to said wipers, means responsive to the disconnection of the calling line from the switch for energizing said magnet a second time, and armature-controlled means operated and effective only in response to the second energization of the magnet for restoring said wipers to normal.

5. In a switching system including an automatic switch having wipers with a normal position and having a single driving means together with a control magnet for causing an operation of said driving means while said magnet is energized to move said wipers in one direction and for causing an operation of said driving means while said magnet is deenergized to move said wipers in another direction, a control unit, means for extending connections from said control unit to said switch, means responsive to the completion of said connections for energizing said control magnet, incoming conductors associated with said control unit over which impulses are received, means in said control unit responsive to each impulse in a series of impulses thereafter received over said incoming conductors for operating said driving means by way of said connections, a changeover relay in the control unit, means responsive to the termination of said series of impulses for operating said relay, means responsive to the operation of said relay for deenergizing said magnet, means for thereafter selectively operating said driving means by way of said connections and for extending said connections to said wipers, means for

energizing said control magnet a second time, and an armature-controlled mechanism operated and effective in response to said second energization of the magnet for restoring said wipers to normal.

6. In a telephone system having a plurality of selective switches with wipers each of which switches has a single driving means together with a control magnet and armature-controlled means for causing an operation of said driving means while said magnet is energized to move the wipers in one direction and for causing an operation of said driving means while the magnet is deenergized to move the wipers in another direction, a control unit, a calling line over which impulses are received, means for extending said line to said unit, a primary one 10 of said switches having connections to said unit, other switches in said plurality of switches accessible to said primary switch, means in said control unit operated when the line is connected to the control unit for energizing the control magnet in said primary switch by way of a 15 first one of said connections, means in said control unit operated responsive to each impulse in a series of impulses for operating said driving means in said primary switch by way of a second one of said connections, means in said control unit operated responsive to the termination of 20 said series of impulses for deenergizing the primary switch magnet, means including said first connection operated responsive to said deenergization for selectively operating the primary switch driving means by way of said second connection, the wipers of said primary switch 25 thereby selecting one of said other switches, means operated responsive to said selection for extending said connections to said one other switch by way of said wipers and for energizing the control magnet therein by way of said first connection, the fifth-mentioned means 30 operated in response to a second series of impulses for operating the driving means in said one other switch by way of said second connection, the sixth-mentioned means operated in response to the termination of said second 35 series of impulses for deenergizing said last-mentioned magnet, means in said control unit for thereafter selectively operating said last-mentioned driving means by way of said second connection, the wipers of said one other switch thereby moved to a selected outlet accessible thereto, and means for extending said connections to said last-mentioned wipers.

7. In a telephone system, a multi-directional selective switch, a control unit associated with said switch, a calling line, means for extending said line to said control unit, a control magnet in said switch, means for energizing said control magnet, means in said control unit whereby said energizing means is operated when said line is extended to said control unit, a stepping magnet in said switch, means for operating said stepping magnet, means in said control unit whereby said last means is operated responsive to each impulse of a series of impulses received over said calling line, a plurality of groups of multi-directional intermediate selective switches accessible to said first selective switch, means in said first selective switch for selecting one of said groups of intermediate switches, means whereby said selecting means is controlled by each operation of said stepping magnet while said control magnet is energized, means for deenergizing said control magnet, means in said control unit whereby said deenergizing means is operated in response to the termination of said series of impulses, means for selectively operating said stepping magnet, means whereby said last operating means is operated responsive to the deenergization of said control magnet, means in said first selective switch for selecting one of said intermediate switches in said one group, means whereby said second selecting means is controlled by selective operation of the stepping magnet while the control magnet is deenergized, said first selective switch thereby selecting the first accessible idle intermediate switch in said one group, means for energizing the control magnet a second time, means in said

control unit whereby said last operating means is controlled over said calling line, means for restoring said first selective switch to normal, and means whereby said last means is operated in response to a second energization of said control magnet after a first energization and deenergization thereof.

8. In a telephone system as claimed in claim 7, means in said first switch for switching through connections to said selected idle intermediate switch, a second control magnet and a second stepping magnet in said intermediate switch, means including one of said connections for energizing said second control magnet, means whereby said last energizing means is operated responsive to the switching of said connections, means including a second of said connections for operating said second stepping magnet, 10 said last operating means and said fifth-mentioned means cooperating to operate said second stepping magnet in response to each impulse of a second series of impulses received, a plurality of groups of multi-directional connector switches accessible to said selected intermediate 15 switch, means in said intermediate switch for selecting one of said groups of connector switches, means whereby said third selecting means is controlled by the operation of said second stepping magnet while said second control magnet is energized, means for deenergizing said second control magnet, means in said control unit whereby said last-mentioned deenergizing means is operated at the termination of said second series of impulses, means for 20 selectively operating said second stepping magnet, means whereby said last operating means is operated responsive to the deenergization of said second control magnet, means in said intermediate switch for selecting one of the connector switches in said one group, means whereby said fourth selecting means is controlled by each operation of the stepping magnet while the control magnet is deenergized, said intermediate switch thereby selecting the first accessible idle connector in said one group, means including a third of said connections for energizing the second control magnet a second time, said last means also 25 controlled over said calling line by means of said release means, means for restoring said intermediate selective switch to normal, and means whereby said last means is controlled by a second energization of said second control magnet.

9. In a telephone system as claimed in claim 8, means in said intermediate switch for switching through connections to said selected idle connector, a third control magnet and a third stepping magnet in said connector, means including one of said last-mentioned connections for energizing said third control magnet, means whereby said last energizing means is operated responsive to the switching of said last-mentioned connections, means including a second one of said last-mentioned connections for operating said third stepping magnet, said last means and said fifth-mentioned means cooperating to operate said third stepping magnet in response to each impulse of a third and fourth series of impulses received, a plurality of groups of outlets accessible to said connector, means in said connector for selecting one of said groups of outlets, means whereby said last-mentioned selecting means is controlled by the operation of said third stepping magnet while said third control magnet is energized, means for deenergizing said third control magnet, means whereby said last-mentioned deenergizing means is operated at the termination of said third series of impulses, means in said connector for selecting a particular one of the outlets in said one group of outlets, means whereby said last-mentioned selecting means is controlled by the operation of said stepping magnet while said control magnet is deenergized, means including a third one of said last-mentioned connections for energizing said third control magnet a second time, said last means also controlled over said calling line by means of said release means, means for restoring said connector to normal, and means whereby said last means is controlled by a second energization of said third control magnet.

10. In a telephone system having means for establishing local connections to a called line over a switch train including a primary local selector and a connector and having means for establishing toll connections to a called line over a switch train including a primary toll selector and said connector, a ring cut-off relay in said connector, means responsive to the seizure of said connector for operating said relay, means responsive to the completion of a connection to a called line for restoring said relay, means operated and effective in response to said restoration of the ring cut-off relay for ringing said called line, circuit means in a toll switch train for preventing the restoration of said relay, means in said toll selector controlled by a toll operator for opening said circuit means thereby to enable said fourth means to restore said relay to ring the called line, said ringing means thereby being controlled by an operator on toll calls.

11. In a telephone system wherein local connections are established over switch trains each including one of a plurality of primary local selectors and one of a plurality of connectors, wherein a toll board operator establishes toll connections over switch trains each including one of a plurality of primary toll selectors and one of said connectors used for completing local connections, a ring cut-off relay in each connector, means in the connector associated therewith for operating said relay, means whereby said operating means is operated when connections are completed to said connector, a locking circuit including one of said connections for holding said relay operated, means in said connector for transferring said locking circuit from said one connection to a second one of said connections, means in each primary selector for restoring said relay, means whereby said ringing means is operated in response to a restoration of said relay, means in each local switch train whereby said restoring means is operated responsive to said transfer of the locking circuit, means in each primary toll selector for short-circuiting said restoring means, thereby to prevent the restoration of said ring cut-off relay, means whereby said short-circuit means is operated responsive to said transfer of the locking circuit, means for opening said short-circuit means thereby to permit said restoring means to restore the ring cut-off relay, and means whereby said last means is controlled by the toll operator.

12. In a telephone system as claimed in claim 11, said means for restoring the ring cut-off relay comprising a high resistance relay and means for operating said high resistance relay in series with the ring cut-off relay over said locking circuit, thereby to cause said ring cut-off relay to restore.

13. In a telephone system, a connector with one set of wipers for completing local and toll calls, said connector having a single driving means together with a control magnet and magnet controlled means for causing each operation of said driving means while said magnet is energized to move said wipers in one direction and for causing each operation of said driving means while said magnet is deenergized to move said wipers in another direction; a release circuit in the connector; means for extending connections to said connector; means operated when either a local or toll connection is completed to said connector for energizing said magnet; a ring cut-off relay in the connector; means operated responsive to the energization of said magnet for operating said relay thereby to open said release circuit; means controlled over said connection for operating said driving means, for thereafter deenergizing said magnet, and for thereafter again operating said driving means; means operated responsive to said last operation of the driving means for extending said connection to the wipers, for opening said release circuit and for causing a restoration of said ring cut-off relay; means operated and effective only if a toll connection has been extended to said connector for preventing said seventh-mentioned

means for restoring said ring cut-off relay; operator-controlled means associated with said toll connection for rendering said seventh means effective to restore said ring cut-off relay; and ringing means operated in response to the restoration of the ring cut-off relay.

14. In a switching system wherein the switching member of an automatic switch is selectively moved in each of two directions in response to each of two series of impulses received by said switch over either of two sets of incoming conductors associated with said switch, two groups of positions available to said switching member, a control relay in said switch associated with only one of said sets of conductors, means for operating said relay, means whereby said operating means is operated only in response to the termination of a first series of impulses received over said one set of conductors, means for moving said switching member, and means whereby said moving means is operated responsive to the operation of said control relay to move said member a predetermined number of steps, whereby said switching member may be moved to a selected position in one group if said relay is operated and to a selected position in another group if said relay is not operated.

15. In a switching system, a selective switch having two sets of incoming conductors and a switching member with a plurality of positions arranged in two groups, a common control unit with means for transmitting impulses, means for connecting said unit to said switch over either set of conductors, means for selectively moving said member in one direction, means for selectively moving said member in the other direction, means whereby the first and second moving means are operated in response to a first and second series of impulses received over one of said sets of conductors from said control unit, means whereby said first moving means is operated in response to a first series of impulses received over the other set of incoming conductors from said control unit, means whereby said second moving means is operated in response to the termination of said last-mentioned series of impulses, and means whereby said second moving means is again operated in response to a second series of impulses received over the other set of incoming conductors from said control unit, said switching member thereby being stepped to a selected position in one group if the connection is made over the one set of conductors and to a selected position in the other group if the connection is made over the other set of conductors.

16. In a switching system, a selective switch having a first set of incoming conductors over which impulses are received when said switch is seized over said first set of conductors and a second set of incoming conductors over which impulses are received when said switch is seized over said second set of conductors, means for seizing said switch, a switching member in said switch having a plurality of positions arranged in two groups, a single driving means in said switch for moving said member, means for determining the direction in which said member is moved by said driving means, means whereby said determining means is controlled over either set of incoming conductors, means whereby said driving means is operated responsive to a first and second series of impulses received over said first set of conductors thereby to selectively move said member in the one direction and then in the other direction, means whereby said driving means is operated in response to a first series of impulses received over said second set of conductors thereby to selectively move said member in said one direction, means whereby said driving means is operated a predetermined number of times in response to the termination of said last-mentioned series of impulses thereby to move said member over a predetermined number of said positions in said other direction, means whereby said driving means is operated responsive to a second series of impulses received over said second set of conductors thereby to

selectively move said member in said second direction, said member thereby being moved to a position in one group if the switch is seized over said first set of conductors and to a position in the other group if the switch is seized over said second set of conductors.

17. In a combination as claimed in claim 16, means for restoring said switch to normal, and means whereby said restoring means is controlled by said determining means.

18. In a switching system, a selective switch having a first set of incoming conductors over which impulses are received when said switch is seized over said first set of conductors and a second set of incoming conductors over which impulses are received when said switch is seized over said second set of conductors, a switching member in said switch with a plurality of positions arranged in two groups, means in said switch for selectively moving said member in one direction, means in said switch for selectively moving said member in another direction, a control magnet in said switch, an armature on said magnet having two positions, means whereby the position of said armature is controlled over said incoming conductors, means in said switch whereby said first moving means is rendered effective in response to said armature assuming one position, means in said switch whereby said second moving means is rendered effective in response to said armature assuming the other position, means whereby both of said moving means are operated responsive to impulses received over said incoming conductors, and means whereby said second moving means is again operated a predetermined number of times only if said switch is seized over said second set of incoming conductors, the control magnet and all of said means cooperating in response to impulses received to move the switching member to a position in one group if the switch is seized over the first set of conductors and to a position in the other group if the switch is seized over the second set of conductors.

19. In a switch as claimed in claim 18, means for restoring said switch to normal, and means whereby said restoring means is operated when said armature assumes said one position for a second time.

20. In a telephone system, a switch with one set of wipers having access to two groups of outlets and with two sets of incoming conductors over which impulses are received, a control unit, means for connecting said unit to said switch over either set of said conductors, means in said control unit for transmitting impulses over said conductors, a control magnet in said switch, an armature on said magnet with two positions, means whereby said armature occupies one position when said unit is connected to said switch and occupies the other position upon the termination of a first series of impulses transmitted to said switch, means for selectively moving said wipers, means whereby said moving means is controlled for moving the wipers in one direction when said armature occupies one position, means whereby said moving means is controlled for moving the wipers in another direction when said armature occupies the other position, means whereby said moving means is operated in response to a first and second series of impulses received over either set of conductors, a control relay in said switch associated with only one set of said conductors, means including contacts on said magnet for operating said relay, means whereby said relay operating means is operated only in response to the termination of a first series of impulses received over said one set of conductors, and means whereby said moving means is operated a predetermined number of times in response to the operation of said control relay, said control magnet, control relay, and all of said means cooperating to move the wipers to a selected outlet in one group in response to impulses received over said one set of conductors and to a selected outlet in the other group in response to impulses received over the other set of conductors.

21. In a combination as claimed in claim 20, means for restoring said switch to normal, means whereby said restoring means is operated responsive to the armature occupying said one position a second time, and means for causing said armature to occupy said one position a second time.

22. For use in a telephone system, a common control unit with incoming conductors over which impulses are received, a particular first selector associated therewith, said selector having access to a plurality of groups of trunks, certain of said trunks terminating in local switches and certain others of said trunks terminating in distant exchanges, means in said switch for selecting any one of said trunks, means in said control unit whereby said selecting means is operated in response to a series of impulses received over said conductors, means in said control unit for controlling a local switch terminating one of said certain trunks selected by said first selector, means whereby said last controlling means is operated in response to a second series of impulses received, means in said control unit for transmitting impulses over a certain other trunk selected by said first selector to the distant exchange terminating said other trunk, means in said control unit whereby said last means is operated responsive to a second series of impulses and each series thereafter received over said incoming conductors, a repeater associated with a second one of said certain other trunks, a switching relay in said control unit, means for operating said relay, means whereby said relay operating means is operated only when said first selector selects said second other trunk, contacts on said relay, means whereby said contacts are operated in response to the operation of said relay thereby to connect said incoming conductors to said second other trunk and to disconnect all of said control means and said transmitting means therefrom.

23. A common control unit as claimed in claim 22 wherein said means for transmitting impulses to the distant exchange terminating said certain other trunk comprises a circuit including conductors of said certain other trunk, a relay individual to said trunk connected in said circuit, and contact means in said unit for short-circuiting said relay.

24. In a telephone system wherein a common control unit in one exchange receives impulses over a calling line in said exchange and repeats said impulses to a common control unit in another exchange over a trunk line inter-connecting said control units thereby to eliminate the necessity for a repeater on inter-exchange calls, a series relay in said first-mentioned control unit, a line relay in said second-mentioned control unit, a circuit including said trunk line for operating said relays in series with each other, means for completing said circuit, means whereby said last means is controlled by a first series of impulses received over said calling line, means for short-circuiting said line relay, and means whereby said last means is operated in response to each additional impulse received over said calling line.

25. In the combination claimed in claim 24, a high-resistance relay in said second-mentioned control unit, means for operating said high-resistance relay in series with said series relay and for removing said line relay from said circuit, means whereby said last means is operated upon the termination of impulses received over said calling line, said series relay restoring when in series with said high-resistance relay, means for connecting said calling line to said trunk line, and means whereby said connecting means is operated in response to the restoration of said series relay.
